UNITED STATES PATENT OFFICE.

JAMES T. McDONOUGH, OF NEW YORK, N. Y.

CLOTHES-LINE APPARATUS.

1,154,524.

Specification of Letters Patent. Patented Sept. 21, 1915.

Application filed November 21, 1914. Serial No. 873,344.

To all whom it may concern:

Be it known that I, JAMES T. McDONOUGH, a citizen of the United States, residing at New York, in the county of New York and State of New York, have invented certain new and useful Improvements in Clothes-Line Apparatus; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in clothes line apparatus and the object in view is to produce a simple and efficient apparatus of this nature so arranged that the line may be swung from the frame of a window or door and held at different angles while the bar supporting the same is positioned horizontally and in the provision of means for taking up slack, thus avoiding the sections of an endless line winding about each other, means being provided for holding the line bar in a closed position and equalizing the strain upon the same.

My invention comprises various details of construction, combinations and arrangements of parts which will be hereinafter fully described, shown in the accompanying drawings and then specifically defined in the appended claims.

I illustrate my invention in the accompanying drawings, in which:

Figure 1 is an elevation of a portion of a window frame showing the application of my invention thereto. Fig. 2 is a similar view showing the line carrying bar in a closed or upright position. Fig. 3 is a plan view of the clothes line holding bar. Fig. 4 is a detail section on line 4-4 of Fig. 1 of a part of the device, and Fig. 5 is a sectional view on line 5-5 of Fig. 2.

Reference now being had to the details of the drawings by letter, A designates the frame of a window to which a bracket member B is fastened, having preferably mounted upon the pin C a pivotal clip C', carrying a winged screw C², and D designates a bracket member carrying a pivotal screw D' upon which an apertured shank portion E of a disk E' is pivotally mounted.

F designates a pivotal pin projecting from

said disk and has its outer end circumferentially threaded for the reception of the nut G. A clothes line carrying bar H is pivotally mounted upon the pin F, and J is a plate through which the pivot pin F passes and has angled ends which are adapted to bear against the face of the disk, as shown clearly in the sectional view of the drawings, and serving to securely hold the bar from rocking upon its pivot and to guide the latter as it tilts. Said bar has three pulleys, designated respectively by letters N, N' and N², which are journaled between the plates N³ at one end of said bar, said pulleys being provided for the purpose of retaining the clothes line in contact with the pulley N', the pulley N² being used for the same purpose when the bar H is reversed in case the device is mounted on the opposite side of the window.

At the opposite end of the bar is mounted a grooved pulley O about which and between the outer pulleys N and N' a rope M is adapted to pass.

One face of the clothes line carrying bar is provided with a series of indentures Q, and R is a bracket member movable upon the bar and has a cylindrical boss projecting from one face thereof, said boss being 85 internally threaded for the reception of a set screw S, serving to hold said bracket member R in an adjusted position, the rope M being adapted to pass about said boss when the bar is adjusted in a vertical position, as shown in Fig. 2 of the drawings. Said bracket member R, it will be noted, is adjustably held upon the bar by the set screw engaging one or another of the indentures therein and serves as a means for 95 regulating the taking up of slack in the rope.

Mounted upon the frame of the window are the sockets T in which the angled ends of a bracket member T' are journaled. Said bracket member T has an integral socket S' in which a contracted end of the socket member W is mounted and in which socket member a slot W' is formed adapted to receive and support the bar H when the latter is 105 adjusted in a horizontal position, as shown in Fig. 1. A set screw Y is mounted in a threaded aperture in the wall of the socket S' and serves to hold the socket member W in place within the socket S'.

It will be noted that the bracket member T' has a swinging movement; and, when

the set screw Y in the socket S' is free from the swiveled projecting portion of the socket member W when the bar H is mounted in said socket member W, the angle at which it is desired to have the clothes line disposed may be regulated when the bar is still held in a horizontal position.

When the bar is adjusted in the position shown in Fig. 2 of the drawings, the slack in the rope may be taken up by means of the rope passing about the boss of the adjustable bracket R upon the bar and the latter held in place by the set screw which frictionally engages the same and, when in this adjustment, the two parallel portions of the ropes which are adapted to pass about a pulley supported at any suitable location will be prevented from twisting one about the other, the slack being regulated by the raising or lowering of the bracket member R.

What I claim to be new is:—

1. A clothes line apparatus consisting of a bracket member adapted to be fastened to the frame of a window, a swinging clothes line bar pivotally mounted upon said member, pulleys mounted upon the bar and about which an endless rope is adapted to pass, means upon the bar for taking up slack in the rope, a bracket member pivotally mounted

upon the frame, a slotted socket member in said bracket member and adapted to receive said bar, and a set screw carried by the socket of the bracket member and adapted to engage the socket member receiving said bar. 35

2. A clothes line apparatus consisting of a bracket member adapted to be fastened to the frame of a window, a pivotal pin mounted thereon, a disk having an apertured shank portion pivotally mounted upon said pin, a screw projecting from said disk, an apertured clothes line bar and an apertured plate through which said screw passes, said plate having angled portions extending about said bar and its ends bearing against the face of the disk, a nut upon the screw, pulleys journaled upon the bar, a clothes line passing about said pulleys, a slack takeup device adjustably mounted upon the bar and having a boss about which the line 50 passes, a pivotal socket mounted upon the frame of the window, and a screw carried by the socket and designed for engagement with the socket member receiving said bar.

In testimony whereof I hereunto affix my signature in presence of two witnesses.

JAMES T. McDONOUGH.
